UNITED STATES PATENT OFFICE.

WALTER R. CLIFFE, OF HARRISBURG, PENNSYLVANIA.

DUMPING-CAR.

SPECIFICATION forming part of Letters Patent No. 784,105, dated March 7, 1905.

Application filed November 2, 1904. Serial No. 231,125.

To all whom it may concern:

Be it known that I, WALTER R. CLIFFE, a citizen of the United States of America, and a resident of Harrisburg, in the county of Dauphin, State of Pennsylvania, have invented certain new and useful Improvements in Dumping-Cars, of which the following is a specification.

This invention relates to certain new and useful improvements in that class of dumping-cars shown in United States Patent No. 596,478, granted January 4, 1898, to Cashin and Shaffer, and which cars are adapted to discharge from one side of the track.

15 The object of my invention is to perfect a dumping-car of this character which can easily be operated by means of a hand-lever at the end of the car.

With this object in view my invention consists in the peculiar construction, arrangement, and combination of parts hereinafter more particularly described, and then definitely set forth by the claims at the end thereof.

In the drawings which accompany and form part of this application, Figure 1 is an end elevation of a box-car having my improvement applied thereto, and Fig. 2 is a similar view of the same, with the box in the dumping position.

30 Referring now to the details of the aforesaid drawings by numerals: 1, 2, and 3 represent the usual or any desired form of timbers or sills, the timber or sill 2 being connected with the arch-bar 5 of the truck and the timber 1 being pivoted to the timber 2, as indicated at 7. The car-box is supported on the timber or longitudinal sill 1 and may be rocked with said timber on the pivot 7 whenever it is desired to dump the car. The end 40 of the car-box is designated by the numeral 9, and at the left-hand side of the same there is located the door 11, which in effect forms the side of the box when the car-box is in the normal position. This door is rigidly connected to an arm or lever 13, which is pivoted directly to the end of the car-box, as designated at 15. A bell-crank lever 17 is also pivoted on the end of the car-box and has one of its arms, 19, coacting with the arm or lever 13, and its other arm, 21, is connected

with a link or connecting rod 23, which in turn is pivoted to a post or standard 25, preferably supported by the truck. It will of course be understood that all of the parts so far described are duplicated on the opposite end of the truck in order that the parts may be moved simultaneously, and it may also be stated that all of the parts so far described are old and well-known and are shown in the aforesaid Patent No. 596,478, and therefore need no further description. They may of course be changed as occasion may require.

In order that the car-box 9 may be more easily tilted, I employ the following mechanism: I connect a hand-lever 30, which is pivoted at 32 to the lever-bracket 34, and to this hand-lever 30 is pivoted a connecting-bar 36, which is connected to a toggle formed of the two arms or levers 38 and 39, pivoted to each other and to the connecting-bar at 40. One 70 arm or lever 38, of the toggle is connected pivotally with the car-box, as indicated at 42, and the other arm or lever, 39, of the toggle is likewise connected to the lower hinge connection 44. When in the normal or loaded 75 position, the lever or handle 30 is substantially upright, and a link 46 is pivoted to the end of the car-box and is so pivoted that it is capable of engaging the upper end of the lever or handle 30 and locking it in the normal position, as indicated at Fig. 1.

From the foregoing and the accompanying drawings it will be clear that whenever it is desired to tilt the car on its pivot 7, so as to dump or discharge the load, it is merely necessary to disengage or free the lever or handle 30 by moving the link 46 on its pivot, when the operator may move the lever to the right, as shown in the drawings, and this movement, acting through the connecting-rod 36, draws 90 on the central pivot of the toggle so as to move it into the position shown in Fig. 2. This movement of the toggle also draws the pivot 42, and thus tilts the car-box on its pivot 7. In view of the fact that the door 11 is pivoted to the car-box and at the same time is connected, by means of the bell-crank lever 17, with the stationary or immovable standard or post 25, the movement of the car-box has the effect of opening the door, although, as a mat- 100

ter of fact, very little movement is given to the door 11. It will of course be manifest that when it is desired to move the car-box back to its original position after it has been 5 tilted to discharge its contents it is merely necessary to move the lever or handle 30 back to its vertical position, when it will, through the connecting-rod 36 and toggle, push the car-box up into its normal horizontal position, the door at the same time moving into the closed position.

I of course do not limit my invention to the exact construction shown, as changes may be made as may be found necessary, and the 15 scope of the invention is therefore set forth by the appended claims.

What I claim as new is—

1. The combination in a car of the class described, of a tilting car-box having a discharge-opening, a movable door closing said opening, arms pivoted to the car-box and connected with said door, a bell-crank lever connected to the car-box and coacting with the door, whereby the movement of the car-box 20 opens the door, a hand-lever suitably supported, and pivoted connections between said hand-lever and the car-box, whereby the movement of the hand-lever tilts the car-box to dump the same and simultaneously opens 25 the door, substantially as described.

2. In a car of the class described, a tilting car-box having a discharge-opening, a mov-

able door closing said opening, arms pivoted to the car-box and connected to the door, and a bell-crank lever connected to the car-box 35 and coacting with the door, whereby the movement of the car-box opens the door, in combination with a hand-lever suitably supported, and a toggle connected with the car-box, said hand-lever and toggle being connected, 40 whereby the single movement of the hand-lever tilts the car and opens the door, substantially as described.

3. In a car of the class described, a tilting car-box having a discharge-opening, a movable door closing said opening, arms pivoted to the car-box and connected to the door, and a bell-crank lever connected to the car-box 45 and coacting with the door, whereby the movement of the car-box opens the door, in combination with a hand-lever suitably supported, and a toggle connected with the car-box, and means for holding said hand-lever in its normal position, said hand-lever and toggle being connected, whereby the single movement 50 of the hand-lever tilts the car and opens the door, substantially as described.

Signed by me at Harrisburg, Pennsylvania, this 28th day of October, 1904.

WALTER R. CLIFFE.
